UNITED STATES PATENT OFFICE.

WILLIAM DIETER, OF BROOKLYN, NEW YORK, ASSIGNOR TO E. W. BLISS COMPANY, OF BROOKLYN, NEW YORK, A CORPORATION OF WEST VIRGINIA.

AUTOMOBILE TORPEDO.

1,303,038.

Specification of Letters Patent.

Patented May 6, 1919.

Application filed February 26, 1918. Serial No. 219,203.

To all whom it may concern:

Be it known that I, WILLIAM DIETER, a citizen of the United States of America, residing in the borough of Brooklyn, county 5 of Kings, city and State of New York, have invented certain new and useful Improvements in Automobile Torpedoes, of which the following is a specification.

This invention relates to automobile tor- 10 pedoes having automatic steering mechanism, such as the well-known gyroscopic steering mechanism. The purpose of the invention is to make provision for inter- 15 rupting the normal steering after the tor- 15 pedo has completed a predetermined portion of its normal run and to thereupon cause the torpedo to steer in an approximately circular course.

The general nature and objects of the 20 invention are the same as those fully set forth in my application for patent filed February 8, 1918, Serial No. 216,102, to which reference may be made for a general description thereof. The present invention 25 provides certain improvements of or modifications of the apparatus set forth in said application.

According to the present invention instead of providing means extraneous to the 30 ordinary steering engine or servo-motor for dominating it, or forcibly overcoming its operation, the circle steering means is made to include the normal steering engine and to modify its mode of operation so that it shall 35 operate the rudder in the normal manner until the initiation of the circle steering, whereupon it will act to hold the rudder to one side or the other, so as to steer as predetermined to either port or starboard 40 in a circular course. The present invention also provides means for insuring against the possibility of so setting the mechanism as to initiate the circle steering prematurely, or at so early a point in the normal straight 45 run of the torpedo as to endanger the ship from which the torpedo is launched, or other ships near it in the same fleet.

The preferred embodiment of the invention is shown in the accompanying drawings, 50 wherein,—

Figure 1 is a diagram showing the course of the torpedo.

Fig. 2 is a vertical section of the after- 55 portion of the torpedo, illustrating the application of the present invention.

Fig. 3 is a transverse section thereof looking aft, the section being in the plane of the line 3—3 in Fig. 2.

Fig. 4 is a horizontal section through the steering engine or servo-motor. 60

Fig. 5 is a plan of the rudder, the tiller and tiller rod, being in effect a continuation of Fig. 4.

Fig. 6 is an enlargement of the portion 65 of Fig. 3, showing the operation of setting or adjusting the mechanism to initiate the circle steering operation upon a given point in the run.

Fig. 7 is a transverse section on the line 7—7 in Fig. 6. 70

Fig. 8 is a front side elevation, looking from the right in Fig. 6.

Fig. 9 is an enlargement of that part of Fig. 2, showing the cam and air valve, the latter being in section. 75

Referring first to the diagram, Fig. 1, A designates a launching tube and B designates the course of a torpedo launched therefrom. The figures 4,000, 10,000 and 15,000 marked on this course may be taken as indicating yards or meters. B¹ indicates (to a magnified scale) a circular course which may be steered by the torpedo, which in this case commences at 4,000 yards. B² in dotted lines indicates a similar circular course which may 85 commence at 10,000 yards. These figures are given as illustrations, since the circular course may begin at any point after a suitable interval in the run of the torpedo sufficient to carry it far enough away from the 90 point of launching to avoid danger to the torpedo boat from which it is launched, or other vessels of the same fleet. In the illustration given, 15,000 yards is assumed as the total normal straight run of the torpedo. 95

The full lines show the launching of the torpedo in the normal manner by aiming the launching tube at the target. The diagram shows in dotted lines at the left, the ease of the so-called "angle fire" in which the torpedo tube, indicated at A', is aimed in a direction removed by a given number of degrees from the ultimate straight course B of the torpedo, the steering mechanism being set to steer through the circular arc indicated at a, which continues until the torpedo has been steered through an arc of the prescribed number of degrees, whereupon the steering mechanism is released in a well-known manner and thereupon functions nor- 100 105 110

mally to steer the torpedo on its straight course B. In referring to B as a straight course it is understood that this term is used in a general sense, since the steering apparatus, used in torpedoes actually steers a slightly sinuous course, veering alternately to opposite sides of the line of aim, the rudder being thrown alternately to port and starboard in the normal functioning of the gyroscopically-controlled steering mechanism. The course shown at B in the diagram is therefore the general course steered, being the mean of the successive arcs or sinuosities, which would be imperceptible in a diagram on the scale here given.

Referring to Fig. 2, C designates the propeller shaft or shafts for driving in the usual manner the propeller screws which turn in contrary directions. D designates, as a whole, the usual gyroscopic steering mechanism, which comprises a steering engine E (or any other equivalent steering mechanism) which, through the usual tiller rod b operates the tiller c for turning the rudders d. Compressed air from the air flask passes through a pipe f to a pressure-reducing valve g, and thence at reduced pressure by pipe h to the usual superheater F, and thence by pipe i to the engine, which latter (not shown) may be a reciprocating engine or turbine, as preferred. The engine drives in the usual manner the propeller shaft C. All of the parts thus far referred to are customary in torpedoes and may be of the usual or any suitable construction, and form no part of the present invention.

The present invention requires first some suitable form of timing or reducing mechanism for bringing about the initiation of the steering of the circular course at any desired point in the run of the torpedo, and so that this period may be determined by the operator before the launching of the torpedo. In the construction shown, the timing mechanism consists simply of a train of gearing (in the specific form shown comprising a worm 4 on the propeller shaft C, a worm-wheel 5 driven thereby carrying on its shaft a worm 6 which in turn drives a worm-wheel 7 on the shaft of which is a worm 8 which drives a worm-wheel 9), this train terminating in a revolving cam G having a cam projection or tooth j which at the predetermined point in its revolution actuates the mechanism for determining the circle steering.

For accomplishing the circle steering according to this invention, it is essential to terminate the normal steering operation (whereby at repeated intervals the rudder is thrown alternately to port and starboard) and to so operate on the tiller as to throw the rudder to one side and hold it there during the period of steering such circular course. Obviously, this result may be ac-

complished in various ways, as, for example, by discontinuing the alternate movements of the steering engine or by so dominating the latter that its continued alternate movements or efforts are impotent to throw the rudder. In the specific construction set forth in my said prior application the means for accomplishing this result is an air engine or cylinder operated by compressed air which prior to its operation has no effect upon the steering mechanism, but when operated acts to dominate or overcome the action of the steering engine and to hold the tiller and rudder over (or partially so) to either side, so as to steer a circular course in the corresponding direction. According to the present invention no separate air engine is provided, but the steering engine itself is made to serve this purpose. To this end a special air valve is provided which is operated by the cam projection j to admit the compressed air at the proper instant into one end of the steering engine (or so-called servomotor), whereby the plunger is thrown over or held over to one extreme position, notwithstanding the effort of the valve of this engine under control of the gyroscope to reverse the air pressure, and thereby resume the normal steering function of the engine. The preferred construction for accomplishing this will now be described.

A special air valve H is provided which receives air at reduced pressure from the low pressure side of the reducer g through a pipe k. This valve is normally closed, but when opened by the cam j it admits compressed air through a pipe l to one end of the cylinder E of the normal steering engine or servo-motor. This engine is constructed precisely as heretofore, that is to say, it has the usual slide valve 10, piston 11, and piston rod 12, the latter being coupled to the tiller rod b. The effect of thus admitting compressed air through the pipe l is to subject the piston 11 to an air pressure on its forward side in excess of that on its aft side, the difference being due to the area of cross section of the piston rod 12. Hence if the piston happens to be in the position shown in Fig. 4, it is held in that position notwithstanding the subsequent effort of the valve 10 to return it by directing compressed air into the cylinder on the aft side of the piston. If, however, the valve happens to be in an opposite position, with the piston at the forward end of its stroke, the pressure introduced through l overcomes the opposing pressure, and displaces the piston to the aft end of its stroke. It results that the rudder is deflected to or held deflected at the position shown in Fig. 5, so that it steers the torpedo through a circular course, such as indicated at B¹ or B² in Fig. 1.

The air valve H may be of any suitable construction, and should be a leakless valve.

so as to avoid the possibility of accidental or premature admission of compressed air into the forward end of the engine cylinder E. The construction of valve shown in detail in Fig. 9 is the same as that set forth in my previous application, the same letters of reference being used and need not here be again described. It is operated by the cam projection j, pushing in the valve plunger u, which punctures the diaphragm s, thus admitting air from k into l.

It is essential to enable the operator to determine before launching the torpedo at what point in its run the circle steering shall begin, and for this purpose the timing mechanism is made adjustable at will by providing that the cam G may be turned at the outset to any desired position, so as to cause its cam projection j to traverse any required part of its circular course before acting upon the valve stem u. To this end the timing mechanism is so proportioned that the cam G will execute not over one complete revolution during the entire maximum course of the torpedo. If this course is 15,000 yards, for example, the gear 9 carrying the cam G may be proportioned to execute one revolution in 15,000, or somewhat over 15,000 yards. If the circle steering is commenced at, say, 4000 yards, the cam G has to be set initially to bring its projection j to a corresponding fraction of the total circular movement in advance of the operative movement of the stem u; if the circle steering is to begin at any later point in the course, the cam has to be set that much farther back. Means for this purpose is set forth in my said prior application, and consists of a construction whereby the cam G may be disconnected from the terminal gear 9, then turned to the required position, and then reconnected with said gear. According to the present invention the gear 9 and cam G are permanently united, and the gear is itself displaced axially to carry it out of mesh with the worm 8, whereupon it may be turned to the required position, and then restored into mesh with the worm.

The present invention also provides a means whereby it is rendered impossible to restore the cam until it is moved to such position as to insure the operation of the circle steering mechanism at a point beyond the minimum distance (for example 4000 yards) at which the circle steering may safely be initiated.

The practical construction is that best shown in Figs. 6, 7 and 8. The cam G is here shown as riveted or otherwise fixedly united to the gear 9 which is keyed or otherwise fixedly united to a longitudinally movable and rotatable spindle w which passes out through a fitting x in the side of the torpedo shell or hull. This spindle has at its outer end a head w' formed with a spe-

cially shaped socket adapted to receive a special tool such as shown in dotted lines at J which is adapted to engage the socket and pull the spindle outwardly, and thereupon to turn the spindle to any desired position. In the special construction shown the head w' has a socket with radial holes to be engaged by a transverse toe on the key J, whereby the head may be both pulled out and turned. The axial movement accomplished by thus pulling out the head carries the gear 9 out of mesh with the worm 8, as shown in Fig. 6. The parts may then be turned to bring the cam G to the desired position, whereupon the operator pushes back the head w' and restores their parts to operative position, the gear 9 entering again into mesh with the worm 8. To enable the operator to determine in thus setting the mechanism the point in the run at which the circle steering shall begin, an exterior circular graduated scale is provided which may be arranged as shown in Fig. 8 where the graduations z are marked on the rim of the head w', and are read with reference to a pointer y marked on the rim of the fitting x. On the graduated scale a portion or zone z' shown in black in Fig. 8 is so marked as to indicate the forbidden zone of danger, being that within the point (for example, 4000 yards) at which it is determined unsafe to start the circle steering.

An important object of the present invention is to provide positive means for safeguarding against the accidental setting of the circle steering means to begin to function within this forbidden or unsafe zone. This is accomplished by providing means which when the cam is axially displaced in order to turn it to position for determining at what point in the run the circle steering shall begin prevents the restoration of the cam so long as it remains within the danger zone, and permits its restoration only after it has been rotatably displaced to a point beyond such zone. It is best accomplished by providing a spring pawl or detent 14 carried by the spindle w and coacting with an arc-shaped ledge 15 mounted through the medium of a connection 16 upon the fitting x or other suitable stationary part. The ledge 15 comprises an arc of such number of degrees as equals the forbidden zone z' (allowing for the thickness of the pawl 14). In the normal or operative position of the cam and other parts the pawl 14 is out of engagement with the ledge 15, as shown in Fig. 3. In pulling back the spindle w to the position shown in Fig. 6, this pawl 14 passes the ledge 15 and springs out behind it as shown. Then if any effort is made to restore the spindle w without turning it enough to bring the pawl 14 beyond the ledge 15, the engagement of these parts blocks and prevents the restoration of the spindle w and holds the gear 9

out of mesh with the worm 8, and therefore inoperative. But when the spindle has been turned to any point beyond the danger zone α' , the pawl 14 is carried beyond the ledge 15 and the spindle may then be freely restored. Any suitable construction of spring-pressed pawl may be used in place of the precise construction shown, and the ledge 15 may be variously mounted and applied, it being only essential that in the coaction of these two parts they shall engage and prevent the restoration of the cam until turned beyond the forbidden zone. Thus a positive safeguard is provided against any inadvertent setting of the mechanism to cause the torpedo to prematurely begin its steering in a circular course.

What I claim is:—

1. In a torpedo comprising propelling and automatic steering mechanism adapted normally to steer a straight course, means for causing the torpedo after traversing part of its normal straight run to then steer a circular course, such means comprising a timing device for bringing it into action at a determined point in the run of the torpedo, and means supplemental to the normal steering control for controlling said steering mechanism to cause it to hold the rudder to one side.
2. In a torpedo according to claim 1, wherein the steering mechanism comprises a steering engine, the controlling means supplemental to the normal means for controlling said engine, adapted to admit fluid under pressure to said engine, whereby to force it or hold it to one position.
3. In a torpedo according to claim 1, wherein the steering mechanism consists of a compressed air engine, the controlling means comprising an air valve operated from the timing device, such valve being additional to that of said engine, and a connection therefrom to one end of the cylinder of said engine, whereby on the opening of said

air valve it presses the piston thereof to the opposite end of the cylinder.

4. In a torpedo comprising propelling and automatic steering mechanism, means for causing the torpedo, after traversing part of its run, to then steer a circular course, such means comprising a timing device for bringing it into action at a determined point in the run of the torpedo, a means for controlling the tiller to hold the rudder to one side, such timing device comprising a reducing train driving a terminal member, the latter adapted for angular displacement whereby to determine at what point in the run of the torpedo such circle steering shall commence, and safety means for preventing the setting of said terminal member in such position as to commence such circle steering prematurely.

5. In a torpedo according to claim 4, such safety means comprising an arc-shaped part, and a reciprocally engaging part, the one stationary and the other movable, adapted when in engagement to prevent the setting of the circle steering mechanism so as to institute prematurely the steering of the circular course.

6. In a torpedo according to claim 4, a cam driven by said reducing train, and setting means adapted to axially displace said cam to enable it to be turned to an angular position corresponding to the point in the range at which the circle steering shall begin.

7. In a torpedo according to claim 4, the terminal gear of the reducing train adapted for axial displacement to bring it out of mesh with its driving member of said train and permit it to be displaced angularly for determining at what point in the run of the torpedo the circle steering shall commence.

In witness whereof, I have hereunto signed my name.

WILLIAM DIETER.
